(57) **CLAIM**

The ornamental design for a pipe connector, as shown and described.

DESCRIPTION

FIG. 1 illustrates a top left perspective view of a pipe connector incorporating the new design;

FIG. 2 illustrates a front elevation view thereof;

FIG. 3 illustrates a rear elevation view thereof;

FIG. 4 illustrates a left side elevation view thereof;

FIG. 5 illustrates a right side elevation view thereof;

FIG. 6 illustrates a top plan view thereof;

FIG. 7 illustrates a bottom plan view thereof; and,

FIG. 8 illustrates a front, cross-sectional view taken along line 8-8 of FIG. 6.
